UNITED STATES PATENT OFFICE.

JOHN R. VOSE, OF ASHLAND, AND WALTER J. OWENS, OF CATLETTSBURG, KENTUCKY.

APPARATUS FOR CLEANING MOTION-PICTURE FILMS.

1,218,137.

Specification of Letters Patent.

Patented Mar. 6, 1917.

Application filed July 5, 1916. Serial No. 107,556.

To all whom it may concern:

Be it known that we, JOHN R. VOSE and WALTER J. OWENS, citizens of the United States, said VOSE residing at Ashland and said OWENS residing at Catlettsburg, both in the county of Boyd and State of Kentucky, have invented certain new and useful Improvements in Apparatus for Cleaning Motion-Picture Films, of which the following is a specification, reference being had therein to the accompanying drawing.

This invention relates to improvements in an apparatus for cleaning motion picture films, one object of the invention being the provision of a method and apparatus in which the film is cleaned in transit, the same being led through a cleaning solution where the liquid adherents are dissolved and the adherent particles are precipitated, a rinsing fluid in a separate compartment being provided to thoroughly rinse the film so that all adhering particles are removed therefrom, there further being provided means for drying the film so that as the film is removed from one reel to another, the same is thoroughly cleaned and dried.

A further object of this invention is the provision of an apparatus of this type in which the film is threaded between rollers and brushes, all of which are power driven so that no strain is placed upon the film during the cleaning, rinsing, and drying operation thereof.

In the accompanying drawings:—

Figure 1 is a side elevation of the complete apparatus made according to and embodying the present invention.

Fig. 2 is a longitudinal sectional view through the tank.

Fig. 3 is a top plan view thereof.

Fig. 4 is a cross section taken on line 4—4 of Fig. 2.

Fig. 5 is an enlarged detail view showing the brush construction for wiping the film.

Figs. 6 and 7 are detail views of one modification of blower nozzle for drying the film.

Referring to the drawings, the numeral 10 designates the base or support which has mounted thereon the standard 11 which holds the tank 12.

This tank 12 is clearly illustrated in Figs. 2 and 3, and is provided with a centrally disposed transverse partition 13 which di-

vides the compartment into the cleaning fluid chamber 14 and the rinsing fluid chamber 15, the valved outlets 16 and 17 being provided so that said compartment may be drained. The cover 18 may or may not be provided.

Carried at one end of the framework 11 at the inlet end of the tank is a reel support 19 for the film carrying reel 20, the film 21 being led in from the guide sprocket 22 and below the submerged guide sprocket 23 mounted within the chamber 14, over the guide sprocket 27 adjacent the upper edge of the partition 13, below the guide sprocket 28 within the compartment 15 and the final guide sprocket 29 within the compartment 15.

Mounted within the compartment 14 are the two pairs of rotary brushes 24 and 25 which are driven by the gears 26 in unison and at a slightly greater speed than the guide rollers, so that a better brushing action will be imparted thereto to brush any adhering matter from the film, these brushes being rotated in an opposite direction to the film so as to brush the adhering material into the respective compartments.

In the compartment 15 are also mounted two pairs of rotary brushes 24' and 25' which are constructed similarly, one of the brushes 24' being submerged. All of the various rollers and brushes are driven by a belt or otherwise, as illustrated in Figs. 1 and 3.

Carried by the bracket 33 at the outlet end of the tank and supported from the frame 11 are the two guide rollers or sprockets 34 and 35 which receive the film as it leaves the tank, and these brackets also support the rotary blower 30 having the tube 31 connected to the nozzle 32 which is a U-shaped device through which the film 21 may be passed and be acted upon by the blasts of air, so that any liquid that may be carried thereby and which is of a highly volatile nature will be evaporated before passage over the roller 34 and before being wound upon the reel 42 mounted in the bracket 41 and provided with the operating handle 43.

Mounted in the shaft 40 at the opposite side to the handle 43 is a pulley 36 which has passed thereover the belt 37 by means of which the various rollers and brushes within

the tank 12 are operated as the wind-on reel 42 is rotated.

From the foregoing description, the method or operation is fully understood, 5 briefly stated as follows:—

The cleaning fluid is placed in the compartment 14 and the rinsing fluid is placed in the compartment 15, both of these fluids in practice being the same, but inasmuch as 10 the first immersion of the film removes the greatest portion of the dirt and oil, it has been found desirable to use two baths, as here illustrated.

The framework, which carries all of the 15 respective guide rollers and which may be lifted out of the tank 12 so that the film 21 may be threaded therethrough, is properly positioned with the film thereon so that the parts will assume the position as shown in 20 Figs. 1 and 2.

The rotary blower 30 is then started, the same being preferably an electrically operated device, and the crank 43 is rotated by the operator and operates the various rollers 25 and brushes and at the same time winds the film upon the reel 42, the film being drawn through the fluid in the compartment 14, while the respective rotary brushes act thereupon to assist in releasing any adhering 30 particles, such as carbon or metal, that adhere to the film during the movement thereof through the projector, the great majority of such adhering material being removed in the compartment 14 and being precipitated 35 to the bottom thereof and commingled with the solution.

The portion of the film previously acted upon is then passed through the solution in the compartment 15 where any remaining oil 40 or foreign matter may be removed therefrom, the nozzle 32 acting upon the film in

transit so that before the same is wound upon the reel 42, it is thoroughly dried.

In practice, it has been demonstrated that the film can be cleaned at approximately the 45 same speed that it moves through the projector in making an exhibition.

What we claim as new is:—

1. A film cleaning apparatus, including a reservoir divided into two separate liquid 50 containing compartments, film guides located in each compartment and above the division wall therebetween, a plurality of pairs of brushes mounted in each compartment, one brush of one pair being adapted to 55 be immersed.

2. A film cleaning apparatus including a tank divided transversely by a partition of lesser height than the walls of the tank into a cleaning and rinsing compartment, a guide 60 roller journaled in each compartment at substantially the same level and below the upper edge of the partition, an intermediate guide roller journaled in the tank adjacent the upper edge of the partition, two pairs of 65 brushes journaled in the tank adjacent the cleaning compartment one pair upon each side of the first mentioned guide roller, the lower brush of one of the pairs being adapted to be immersed, two pairs of rotary 70 brushes journaled in the rinsing compartment adjacent the exit end thereof, the upper roller of one of the pairs being adapted to be immersed in the rinsing fluid, and two guiding rollers one adjacent the entrance end of 75 the cleaning compartment and the other adjacent the exit end of the rinsing compartment.

In testimony whereof we affix our signatures.

JOHN R. VOSE.
WALTER J. OWENS.
